Des. 1601

Thomas G. Bering, of Philadelphia, Pa.
Letters Patent No. 1601-dated June 3, 1862.

The schedule referred to in these Letters Patent and making part of the same.

To all whom it may concern:

Be it known that I, Thomas G. Bering, of the city of Philadelphia, in the State of Pennsylvania, have invented or produced a new and original design for a metal fence for inclosing cemetery lots &c. and I do hereby declare that the following is a full and exact description of the same, reference being had to the accompanying drawing, making a part of this specification, and to the letters of reference marked thereon.

A being a representation of one section or panel of the fence proper; and B, a representation of the gate or swinging panel; the dotted lines between them indicating the intended position of a supporting post.

The design for the panels A. of the fence proper consists of the moulding c. of the configuration shown in the drawing, in combination with its inclosed configurations d. surmounted by the face e. and the configurations f. ornamented as represented in the drawing.

The design for the swinging panel or gate B. consists of the combination of the scrolls g. and straight portions h. surmounted by the basket of flowers i. the whole being ornamented as seen in the drawing.

I claim the combination of the configurations and ornaments specified, and shown in the panel A. and as a design for the fixed panel of a fence. the combination of the configurations and ornaments specified and shown in the panel B. as a design for a fence.
